UNITED STATES PATENT OFFICE.

NELS H. WHEELER AND NEIL M. NEWHOUSE, OF CORVALLIS, OREGON.

DEVICE FOR SWAGING INSERTIBLE SAW-TEETH.

SPECIFICATION forming part of Letters Patent No. 364,877, dated June 14, 1887.

Application filed June 24, 1886. Serial No. 206,177. (No model.)

To all whom it may concern:

Be it known that we, NELS H. WHEELER and NEIL M. NEWHOUSE, of Corvallis, in the county of Benton and State of Oregon, have 5 invented a new and useful Improvement in Devices for Swaging Insertible Saw-Teeth, of which the following is a specification.

Our invention is in the nature of a new machine or device for operation by hand, whereby to old insertible saw-teeth which have become worn and unserviceable from use may be renewed or restored to shape and rendered serviceable by drawing, swaging, and roll-tempering the same.

15 It consists in the peculiar construction and arrangement of parts forming said device, which I will now proceed to describe with reference to the accompanying drawings, in which—

20 Figure 1 is a side elevation with the handle of the lever broken off, and showing in dotted lines the different positions of the lever. Fig. 2 is an end elevation of the same. Figs. 3 and 4 are detached views in perspective of the 25 swage-blocks A and B, shown in Figs. 1 and 2. Fig. 5 is a detail view of the pin for retaining the tooth in the swage-block while being acted upon. Fig. 6 is the holder for securing the pin. Fig. 7 is the fulcrum-bolt for 30 the lever C. Fig. 8 is the clamping-bolt for holding the two parts of the swage-block together. Fig. 9 is a detail of the cam-headed lever. Fig. 10 is a view of the form of insertible saw-tooth that our device is intended to 35 operate upon. Figs. 11 and 12 are keys for tightening the two swage-blocks in their locked connection to each other and sustaining the strain between them.

40 A is the main swage-block, in whose upper face is formed a groove or slot, *g f*, of a width and shape to receive the insertible tooth *E*. The other portion, *B*, of the swage-block is fastened to *A* by a clamping-bolt, *F*, which passes through a hole, *c*, in block *A*, and through a 45 slot, *c'*, in the block *B*, the slot *c'* permitting the block *B* to be set higher or lower, according to the thickness of the saw-tooth. The upper end of the block *B* is slotted to receive the swaging-lever *C*, which is formed with an 50 eccentric or cam head, and which head, as well

as the end of the block *B*, are perforated to receive the fulcrum-bolt *a*. The block *A* is formed with an offset or shoulder, *d*, and above this there are two flanges, *i i*, at the edges, between which the sides of the block *B* are seated 55 and held. A lip, *e*, is also formed at the lower end of block *B*, which lip projects under the shoulder *d* of the block *A*. Between this lip *e* and shoulder *d* the tapered keys *G G* are driven from opposite sides to tighten up the 60 two blocks in their proper relation to each other and to afford a broad bearing to carry the strain when block *B* is forced up and block *A* forced down by the action of the cam-lever.

65 D is a pin which fits a half-round notch in the tooth *E*, and affords a means for holding it against slipping during the drawing and swaging action of the lever. This pin is coupled at one end to and held by a holder, *H*, which passes through a hole, *b*, on the block, while 70 the other end of the pin *D* is grasped by the thumb and finger of the left hand, the lever *C* being worked by the right hand.

In operating the device the swage-blocks, 75 after being adjusted in relation to each other for the proper size of tooth, are firmly seated in a vise or special socket. The old tooth is then placed at a cherry-red heat in the groove *g f*, and the pin *D* is then laid across it, resting in the half-round notch. The outer end 80 of the pin being then held by the fingers of the left hand, the lever *C* is with the right brought from the position shown in full lines successively through the positions shown in dotted lines, during which movement the cam-head 85 of the lever draws and swages the old worn tooth to its proper configuration at the point, and at the same time gives it a roll-temper, thus making the old and unserviceable tooth 90 as good as new.

We prefer in constructing the device to make it entirely of steel; but in any case a hardened steel plate is detachably fastened in the bottom of the groove or seat *g f* for the saw-tooth.

95 Having thus described our invention, what we claim as new is—

1. The combination of swage-block *A*, having shoulder *d* and hole *c*, the block *B*, with lip *e* and slot *c'*, the clamping-bolt *F*, and the 100

eccentric-headed or cam-lever C, fulcrumed to block B, substantially as and for the purpose described.

2. The combination of swage-block A, having shoulder d, hole e, and tooth-seat g f, the block B, with lip e and slot e', and the eccentric-headed or cam-lever C, fulcrumed to the block B, substantially as and for the purpose described.

3. The combination, with the swage-blocks A B, connected by a clamping-bolt and having shoulder d and lip e, of the tapered keys G G' and the swaging-lever C, substantially as and for the purpose described.

4. The combination, with the two blocks A 15 and B, connected together, substantially as described, the former having a tooth-seat or groove, g f, and hole b, of the holding-pin D and pin-holder H, arranged in the hole b, and the swaging-lever C, substantially as and for 20 the purpose described.

Signed and witnessed.

NELS H. WHEELER.
NEIL M. NEWHOUSE.
